RECORDING OF SOUND

Glenn L. Dimmick, Audubon, N. J., assignor to
Radio Corporation of America, a corporation
of Delaware

Application November 2, 1935, Serial No. 47,968

9 Claims. (Cl. 179—100.3)

This invention relates to the recording of sound or the like, and has for its principal object the provision of an improved apparatus and method of operation for obviating certain kinds of distortion which tend to occur in the reproduction of sound from a multiple track or push-pull record such as that disclosed by my copending application Serial No. 674,805, filed June 8, 1933 and assigned to the same assignee as the present application.

As pointed out in the aforesaid copending application, the distortion caused by fogging of the record valleys and under-exposure of the record peaks is avoided by the provision of two similar sound tracks displaced in phase by 180 degrees and arranged to be simultaneously reproduced and combined for operating a loudspeaker or the like. While the types of recorder disclosed by the aforesaid application obviate the distortion mentioned above, their operation sometimes involves the difficulty that the separate sound tracks tend to overlap at high modulation and are not readily reproduced without distortion when such overlapping occurs. In accordance with the present invention, such distortion of the reproduced sound is minimized or avoided by the provision of means for producing a light beam of such configuration that the two sound tracks are maintained in spaced relationship with one another irrespective of the extent to which they are modulated.

As hereinafter indicated, one suitable means of determining the contour or shape of the light beam is a mask having an aperture provided with a central portion having its edges sloped with respect to a cooperatively associated light slit and with end portions having their opposed or inner edges perpendicular to the light slit and spaced apart to maintain a predetermined spacing between the two record tracks. For convenience of expression, this aperture is sometimes hereinafter designated as having the form of a parallelogram offset at its opposite ends.

The invention will be better understood from the following description when considered in connection with the accompanying drawing, and its scope will be pointed out in the appended claims.

Referring to the drawing,

Fig. 1 is a diagrammatic showing of a recorder constructed in accordance with the invention,

Fig. 2 illustrates the form of the light beam and its relation to the light slit, and

Fig. 3 illustrates the type of record produced by the recorder.

The recorder includes a light source 10 from which light passes through a lens 11, the aper-

ture 12 of a mask 13 and a lens 14 to the galvanometer recorder mirror 15 which is vibrated in accordance with the signals to be recorded. Light is reflected from the mirror 15 through a lens 16, the light slit 17 of a screen 18 and lenses 19 and 20 to the light sensitive surface of a record strip 21 which is supported upon and moved over the surface of a roller 22.

The image of the aperture 12 reflected by the mirror 15 on the member 18 is indicated at 23. As will be readily understood, this image is in the form of a parallelogram offset at its opposite ends, is vibrated transversely of the slit and produces two sound tracks 24 and 25 (Fig. 3) which are displaced 180 degrees with respect to one another and which are spaced apart at their highest peaks by a distance dependent on the horizontal spacing between the edges 27 and 28 of the offset portions of the aperture 12. This form of aperture has the advantage that overshooting of the light beam due to excessive modulation can not cause one of the record tracks to extend over into the area normally occupied by the other and that the distortion heretofore resulting from such excessive modulation is avoided.

I claim:

1. A signal recorder including means defining a light slit, means for producing a light beam having the form of a parallelogram offset to space its ends from one another along the length dimension of said slit, and signal responsive means operable to vibrate said beam across said slit transversely to said dimension.

2. A signal recorder including means defining a light slit, means for producing a light beam having the form of a parallelogram offset to space its ends from one another along the length dimension of said slit, signal responsive means operable to vibrate said beam across said slit transversely to said dimension, a light sensitive record, and means for moving said record transversely of the light transmitted through said slit.

3. A sound recorder of the galvanometer type including means defining a light slit, means for producing a light beam provided with a central portion angularly disposed with respect to said slit and with end portions perpendicular to and spaced apart along said slit, and means for vibrating said beam across said slit.

4. In an apparatus for producing sound tracks displaced in phase with respect to one another, the combination of means for producing a light beam having its end portions spaced apart and angularly disposed with respect to its central

portion, means defining a light slit, and signal responsive means operable to vibrate said beam across said slit.

5. In an apparatus for producing sound tracks 5
180 degrees out of phase with one another, the combination of means defining a light slit, means for producing a light beam having its end portions spaced apart longitudinally of said slit and angularly disposed with respect to its central 10 portion, and signal responsive means operable to vibrate said beam across said slit in a direction parallel to the side edges of said end portions.

6. In a signal recorder including means defining a light slit and signal responsive means operating to vibrate a light beam transversely across said slit, means for producing a light beam having the form of a parallelogram offset to space its ends from one another along the length dimension of said slit. 15

15. 7. In a signal recorder including means defining a light slit, signal responsive means operable to vibrate a beam of light transversely across said slit, a light sensitive record, and means for 20

moving said record transversely of the light transmitted through said slit, means for directing a beam of light having the form of a parallelogram offset to space its ends from one another along the length dimension of said slit to said 5 signal responsive means.

8. In a sound recorder of the galvanometer type including means defining a light slit and means for vibrating a beam of light across said slit, means for producing a light beam provided with a central portion angularly disposed with respect to said slit and with end portions perpendicular to and spaced apart along said slit. 10

9. In an apparatus for producing sound tracks displaced in phase with respect to one another 15 and including means defining a light slit and signal responsive means operable to vibrate a beam of light across said slit, means for producing a light beam having its end portions spaced apart and angularly disposed with respect 20 to its central portion.
